[57] CLAIM

The ornamental design for a dispenser for pulverous
and granular substances, as shown and described.

DESCRIPTION

FIG. 1 is an exploded, perspective view of a dispenser
for pulverous and granular substances showing my new
design;

FIG. 2 is an elevational view;

FIG. 3 is a top plan view on a slightly enlarged scale;
FIG. 4 is a top plan view of a modified form of my new
design wherein only the configuration of the top open-
ings has been changed.

FIG. 1**FIG. 2****FIG. 3**FIG. 4
